Fig. 1.

Fig. 2.

Fig. 3.

Fig. 5.

Fig. 4.

FIG. 1 is a perspective view of an igniter element, showing my new design;

FIG. 2 is a side elevational view thereof, the opposite side being identical to the side shown;

FIG. 3 is a top plan view thereof, the bottom having substantially the same appearance;

FIG. 4 is a front elevational view thereof; and

FIG. 5 is a rear elevational view thereof.

The stippled shading indicates a roughened surface.

I claim:

The ornamental design for an igniter or similar article, substantially as shown and described.
